CLAIM

The ornamental design for the combined toothbrush, tube of toothpaste, and container therefor, as shown and described.

DESCRIPTION

FIG. 1 is a front elevational view of the combined toothbrush, tube of toothpaste, and container therefor showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a top, front and left side, exploded assembly view thereof, showing the interior; and,

FIG. 8 is a top, rear and right side, exploded assembly view thereof, showing the interior.

The broken line showing of the words in FIGS. 1, 3, 4, 7 and 8 is for illustrative purposes only and forms no part of the claimed design.
